UNITED STATES PATENT OFFICE.

FREDERICK WILLIAM AUSTIN, OF OLDHAM, ENGLAND.

CHAIN-CONTROLLING MECHANISM FOR TUFTED-PILE-FABRIC LOOMS.

Application filed April 3, 1925. Serial No. 20,445.

To all whom it may concern:

Be it known that I, FREDERICK WILLIAM AUSTIN, a subject of the King of the United Kingdom of Great Britain and Ireland, and 5 resident of 123 Coppice Street, Oldham, in the county of Lancaster, England, have invented new and useful Improvements in Chain-Controlling Mechanism for Tufted-Pile-Fabric Looms, of which the following 10 is a specification.

This invention of improvements in looms for weaving tufted pile fabrics relates to means for moving and guiding the carrying chains used for carrying tube frames for 15 holding spools of yarn for forming tufts and furnished with yarn tubes and conveying such tube frames to and from the places at which they are removed from the chains in order to be used in supplying yarns to 20 form tufts and after being so used are restored to the chains.

This invention consists in driving and guiding mechanism for chains as aforesaid which enabling sprocket wheels within the 25 circuit of the chains carrying tube frames to control the movement of the lower runs of the chains from which tube frames hang and also enabling the lower runs of the circuits of the chains to be properly supported 30 and guided, enables tube frames to be carried and guided properly to and from the place of use in a loom while placed in line two or more together end to end in two or more series for use in the insertion of tuft 35 yarn between the warp threads in the formation of tufted fabrics of great width for which it is necessary to employ three or more chains to carry the two or more series 40 of tube frames placed end to end since in the case of the butting ends of tube frames the butting ends of two tube frames must be engaged with one chain and consequently the use of sprocket wheels in engagement 45 with the outer circuit of such a chain is impracticable.

The driving and guiding mechanism provided according to this invention is applicable also in connection with the movement and guidance of chains carrying tube frames placed end to end in line for use with tuft transferring nippers in looms and of chains used in pairs for carrying single tube frames of any length.

To these ends the invention comprises as 50 is hereinafter more fully explained, sprocket wheels within the circuits of the chains to

be guided and driven and co-operating guides presenting curved guide channels guiding the chains and space for the access of the sprocket wheels to the chains and 60 open channels on the outer sides of the circuits of the chains for the passage of the parts by which tube frames are connected with the chains.

An illustrative embodiment of the invention 65 is shown in the accompanying drawings.

Fig. 1 is a diagrammatic side elevation of a tube frame chain driving and guiding mechanism provided according to this invention and part of a loom to which that mechanism is applied, the carrying chain and sprocket wheels being indicated by dotted lines.

Fig. 2 is a diagrammatic end view of the 75 mechanism shown in Fig. 1.

Fig. 3 is a side elevation on a larger scale than Figs. 1 and 2 of chain driving and guiding mechanism indicated at the upper 80 right hand part of Fig. 1.

Fig. 4 is a transverse section on the plane indicated by the line 4—4 of Fig. 3.

Fig. 5 is a side elevation on a larger scale than Figs. 1 and 2 of the mechanism indicated at the upper left hand end of Fig. 1 85 by which the tube frame carrying chains are conducted to and from the place at which tube frames are removed from and restored to them and parts are held stationary for the removal and restoration of tube frames 90 from and to them.

Fig. 6 is an end elevation of parts shown in Fig. 5 looking in the direction of the arrow 6.

The same numerals of reference indicate 95 corresponding parts in the several figures.

In Figs. 1 and 2, 7 are the side frames of the loom, the other parts of and used in the loom being almost wholly omitted from the figures for simplicity. On each side frame 100 7 is a vertical extension 8 to the upper part of which is secured by bolts and nuts a standard 9 formed at the upper end with a flange or facing 10. A framework of upright rods 11 secured in socket plates 12 at 105 their lower ends bearing on the floor and having socket plates 13 at their upper ends, is arranged at the rear of the loom. The framework is braced by means of diagonal stays 14 connected to collars 15 held in positions of adjustment on the rods 11 by means of set screws or other means. Carried by

and secured to the flanges 10 and the socket plates 13 are two girders 16 of any suitable cross section and, advantageously as shown, formed of two channel irons held at a little distance apart to form a groove 17 between the two channels. Struts 18 are connected to the standard 9 and to the girders 16 to stiffen the framework. The two girders 16 carry bearings 19 for shafts 20 having sprocket wheels 21 serving simply to support and guide the carrying chains 22 and also bearings 191 for a shaft 201 having fast on them sprocket wheels 211 which support and guide and also drive the chains 22. Bearings 23 are also provided on the girders 16 to carry shafts 24 made to receive motion by means of worm wheels 25 from worms 26 on a shaft 27 which is carried in bearings 28 supported by one of the girders 16, and made to receive motion by means of bevel wheels 29 and 30 from an appropriate shaft 31 revolving in the working of the loom. The lower faces of the bearings 19, 191, 23 and 28 have ribs 32 positioning them on the girders 16 by engaging with the grooves 17. The shafts 24 carry sprocket wheels 33 fast upon them which engage at both their upper and lower sides with the chains 22 to be guided and moved and each shaft 24 is provided with as many sprocket wheels 33 as there are chains to be guided. For instance in the case illustrated three chains 22 and three sets of sprocket wheels 33 are shown. The construction enabling each sprocket wheel 33 to engage a chain at parts spaced apart in its circuit is an advantageous means of compelling both such parts to move concurrently. There are also three sprocket wheels on each of the shafts 20, 20 and 201. A worm 35 drives a worm wheel 251 on the shaft 201.

Mounted on the shafts 24 at opposite sides of the sprocket wheels 33 are bosses 36 and suspended from each boss 36 by rods 37 are guides 38 presenting semi-circular or other curved guide channels 39 for the passage of rollers 40 provided on each side of the carrying chains 22.

Each sprocket wheel 33 passes between the two guides 38 with which it is used so as to engage with the chain 22 in the part guided by the guide channels 39.

The rods 37 are secured in the bosses 36 by nuts 371 and at their other ends are secured in forked part 372 to receive ears or lugs 381 on the guides 38 and secured thereto by rods 44 extending transversely through the ears 381 and secured therein by set screws or by nuts as shown in Fig. 4. The rods 44 hold each series of guides 38 accurately in relative position laterally and links 45 connecting such rods 44 also serve to position the guides 38. The rods 44 are omitted from Figs. 1 and 2 for clearness. Figs. 3 and 4 show one of the sprocket wheels 33

and the parts used with it but in general the description applies equally to all the wheels 33.

The guides 38 from which the chains 22 pass to the place 42 at which the tube frames 43 are removed and restored to them are formed as shorter arcs than the other guides 38. Only a few of the tube frames 43 applied to the chains 22 are indicated in Fig. 3. Each tube frame 43 presents end plates 75 adapted to be placed contiguously one against another so that the tube frames 43 can be placed contiguously in line, end to end, to present their yarn tubes in continuous lines and in the case illustrated in which there are three chains 22 made to travel in parallel inner and outer circuits and to carry two series of tube frames 43 side by side, the tube frames 43 are connected in a series of pairs in line to the three chains 22, so that the inner or centre chain 22 is engaged by the contiguous end plates in the middle of each pair while each outer chain is engaged by one end plate only of the tube frames 43 connected with it. The tube frames 43 form no part of the present invention and will therefore not be described in further detail.

The guides 38 in each pair are shown as formed separate and spaced apart and as presenting guide channels 39 towards one another and also presenting by the space between them an open channel on the outer circuit of the chain 22 with which they co-operate so that parts of the end plates for connexion with the chains may pass between the guide and also space for the access of a sprocket wheel to such chain. The two guide channels 39 of a pair may be formed however in one guide with a gap at the top to allow the teeth of the sprocket wheel 33 to enter in order to engage with the portion of the chain 22 below them.

In the case illustrated in Fig. 1 there are four shafts 24 driven by worm wheels 25 and worms 26 and carrying sprocket wheels 33 co-operating with guides 38 so that, with the co-operation of the sprocket wheels 21 shown at the right hand of Fig. 1 and serving simply for guiding the chains 22, the chains 22 hang in four loops 46 but the number of shafts 24 driven by worm wheels 25 and worms 26 and carrying sprocket wheels 33 co-operating with guides 38 may be made greater or less according to the number of loops 46 which may be requisite to accommodate the length of chains 22 needed to carry the tube frames 43 to be used at any time in a loom.

Mounted in brackets 47 secured in suitable position on the loom frames 7 is a shaft 48 provided with sprocket wheels 49 in engagement with the chains 22 and turned step by step by mechanism in the loom and on the shaft 48, as shown most clearly in Figs. 5 and 6 are mounted upwardly extending links 50 formed in parts secured to

gether to allow adjustment of length of the links 50 and supported by or as shown integral with the upper part of the links 50 are blocks 501 forming bearings for a shaft 51 provided with sprocket wheels 52 one to engage each chain 22 at two parts spaced apart in the circuit and for co-operation with each sprocket wheel 52 there are provided at each side of the chain 22 engaging it two other curved guides 53.

The guides 53 are provided with brackets 531 with square sockets to fit around square projections on the bearing blocks 501 and are formed as shorter arcs than the other guides 38 and each being formed similarly to the guides 38 serves to hold the chain 22 guided by it in engagement with the co-operating sprocket wheel 52.

In Fig. 2, 54 are two of the jacks of the loom and in Figs. 1, 2 and 5, 55 is a strut extending across the loom to hold the brackets 47 in relative position. The strut is attached to brackets, not shown, fixed on the brackets 47.

25 The intermittent turning of the shaft 48 causes parts of the chains 22 to be brought successively into position for the removal of the tube frames 43 from the chains 22 and held stationary while tuft yarn is drawn from the tube frames 43 for the formation of tufts and while the tube frames 43 are being restored to the chains 22.

The action of the shaft 48 turned intermittently and at other times held stationary co-operating with the continuous movement of the shafts 20, 24, 201 turned by the worm wheels 25 and 251 causes the guides 53 and shaft 51 supported by the shaft 48 and the sprocket wheels 52 thereon to swing backwards and forwards alternately about the shaft 48 as the loops 56 of chain 22 approaching and leaving them, vary in length.

Chains 22 are caused to pass to the guides 53 in a slightly curved path with no abrupt turns and the slack of the chains 22 between the guides 53 and 38 and sprocket wheels 211 allows for the oscillatory movement of the guides 53, shaft 51 and sprocket wheels 52.

50 The sprocket wheels 21 mounted on the shafts 20 run freely, serving merely to support and guide the carrying chains 22.

The sprocket wheels 33 engaging with the chains 22 in the parts guided by the guides 38 maintain in constant length the festoons or loops 46 of chain 22 hanging from the guides 38 and the sprocket wheels 21 whatever may be the length given to such festoons or loops 46 when the chains 22 are being adjusted on the sprocket wheels 33, 21.

The shaft 48, sprocket wheels 49 on the intermittently turned shaft 48 and the shaft 51 and the sprocket wheels 52 carried by the links 50 ensure that equal lengths of the chains 22 shall approach and leave the place

42 where portions are held stationary while the movement of the sprocket wheels 52 about the shaft 48 allows for the variation in the lengths of the parts 56 of the chains 22 extending between the sprocket wheels 52 and the sprocket wheels 211 and the nearest guide 38 enabling the intermittent movement and stoppage of parts of the chains 22 easily to be effected while the rest of the chains 22 is moved steadily. The sprocket 75 wheels 52 and guides 53 work in a similar manner if the movement of the chain 22 be reversed from time to time instead of being moved in one direction only.

In carrying this invention into effect various changes may be made in the details of construction.

What I claim is:—

1. In a chain controlling mechanism for a tufted pile fabric loom, endless chains in parallel circuits, each chain provided with guide-engaging devices projecting from its opposite sides, chain-guides with opposed curved guide-channels in spaced opposed faces presenting by the inner curved walls of the guide-channels runways for the projecting engaging devices of the chains and presenting exteriorly of the chain circuits open channels between the opposed faces and also presenting spaces interiorly of the chain circuits, sprocket wheels within the chain circuits projecting into said spaces and engaging said chains at parts engaging said guides, means of connection ensuring equal circumferential movement of the sprocket 100 wheels engaging different chains, means for supporting said sprocket wheels and means for supporting said guides.

2. In a chain controlling mechanism for a tufted pile fabric loom, endless chains in parallel circuits, each chain provided with guide-engaging devices projecting from its opposite sides, chain-guides with opposed curved guide-channels in spaced opposed faces presenting by the inner curved walls 110 of the guide-channels runways for the projecting engaging devices of the chains and presenting exteriorly of the chain circuits open channels between the opposed faces and also presenting spaces interiorly of the chain circuits, sprocket wheels within the chain circuits projecting into said spaces and engaging said chains at parts engaging said guides, means of connection ensuring equal circumferential movement of the sprocket 115 wheels engaging different chains, means for supporting said sprocket wheels, means for supporting said guides and means for turning said sprocket wheels.

3. In a chain controlling mechanism for a tufted pile fabric loom, endless chains in parallel circuits, each chain provided with guide-engaging devices projecting from its opposite sides, chain-guides with opposed curved guide-channels in spaced opposed 125 faces presenting by the inner curved walls 130 of the guide-channels runways for the projecting engaging devices of the chains and presenting exteriorly of the chain circuits open channels between the opposed faces and also presenting spaces interiorly of the chain circuits, sprocket wheels within the chain circuits projecting into said spaces and engaging said chains at parts engaging said guides, means of connection ensuring equal circumferential movement of the sprocket 135 wheels engaging different chains, means for supporting said sprocket wheels, means for supporting said guides and means for turning said sprocket wheels.

faces presenting by the inner curved walls of the guide-channels runways for the projecting engaging devices of the chains and presenting exteriorly of the chain circuits, 5 open channels between the opposed faces and also presenting spaces interiorly of the chain circuits, a shaft, sprocket wheels within the chain circuits and fixed upon the shaft and projecting into said spaces and engaging 10 said chains at parts engaging said guides, means for supporting said shaft and means for supporting said guides.

4. In a chain controlling mechanism for a tufted pile fabric loom, endless chains in 15 parallel circuits, each chain provided with guide-engaging devices projecting from its opposite sides, chain-guides with opposed curved guide-channels in spaced opposed faces presenting by the inner curved walls 20 of the guide-channels runways for the projecting engaging devices of the chains and presenting exteriorly of the chain circuits open channels between the opposed faces and also presenting spaces interiorly of the 25 chain circuits, a shaft, sprocket wheels within the chain circuits and fixed upon the shaft and projecting into said spaces and engaging

said chains at parts engaging said guides, means for supporting said shaft, means for supporting said guides and means for turning 30 said shaft.

5. In a chain controlling mechanism for a tufted pile fabric loom, endless chains in parallel circuits, each chain provided with guide-engaging devices projecting from its 35 opposite sides, chain-guides with opposed faces presenting by the inner curved walls of the guide-channels runways for the projecting engaging devices of the chains and presenting exteriorly of the chain circuits, open 40 channels between the opposed faces and also presenting spaces interiorly of the chain circuits, a shaft, means for supporting said shaft, suspending means mounted on said shaft and connected to said chain guides, means for turning said shaft and sprocket wheels within the chain circuits and fixed 45 upon the shaft and projecting into said spaces and engaging said chains at parts engaging said guides. 50

In testimony that I claim the foregoing as my invention, I have signed my name this twentieth day of March, 1925.

FREDERICK WILLIAM AUSTIN.
